UNITED STATES PATENT OFFICE.

WILLIAM H. CATTELL, OF DECATUR, ILLINOIS, ASSIGNOR OF ONE-HALF TO
FLETCHER T. PHILLIPS, OF SAME PLACE.

DESIGN FOR A CASING AND SUPPORT FOR COIN-ACTUATED WHEELS.

SPECIFICATION forming part of Design No. 27,579, dated August 24, 1897.

Application filed January 16, 1897. Serial No. 619,496. Term of patent 3 $\frac{1}{2}$ years.

To all whom it may concern:

Be it known that I, WILLIAM H. CATTELL, of Decatur, in the county of Macon and State of Illinois, have invented a certain new Design for a Support and Casing for Coin-Actuated Wheels, of which the following is a specification.

In the drawings herewith accompanying, Figure 1 represents a side elevation of a structure showing my design, and Fig. 2 is a front view of the same.

The design consists in the shape of the structure and in the configuration of its face, as will hereinafter more fully appear.

15 The casing for the wheel comprises a circular frame 1, which stands obliquely, forming an angle of about thirty degrees with the vertical. Its face has a recess at 3 that is covered with glass and bordered by a molding 2. 20 The recess is circular and concentric with the circle of the frame and it occupies the greater portion of the face of the casing. In the center of the recess a circular mirror 4 stands out from the back of the recess, and such mirror has a frosted or otherwise ornamented border, as suggested at 5, which surrounds its outer edge. The back of the frame is swelled outward by moldings, as shown at 10 in Fig. 1.

25 The support for the casing comprises a vertical pedestal seated on a circular base 8, the perimeter of which is molded. The sides of

the pedestal are vertical and parallel and the bottom thereof extends from front to back of the base. In side elevation the pedestal 35 consists of two conjoined members, one in front and the other in the rear. The rear member rises with a curved forward inclination and spreads in curved lines at its upper termination. Its upper forward surface has 40 the same inclination as the back wall of the wheel-casing and it is joined thereto. The front member of the pedestal rises in front in a vertical line from the base to the lower front edge of the wheel-casing, as shown at 45 7. It joins the lower edge of the wheel-casing, and its rear wall curves downward and backward until it merges into the upward curve of the front wall of the rear member of the pedestal. The front surface of member 7 is recessed, and the opening is closed by a strip of glass, as shown at 9 in Fig. 2.

Having thus described my invention, what I claim, and desire to secure by Letters Patent, is—

55 The design for a casing and support for coin-actuated wheels, substantially as shown and described.

In testimony whereof I sign my name in the presence of two subscribing witnesses.

WILLIAM H. CATTELL.
